UNITED STATES PATENT OFFICE

2,007,216

GAME

Newman Le Roy Rogers, Los Angeles, Calif.

Application January 29, 1934, Serial No. 708,812

4 Claims. (Cl. 273—138)

My invention relates to a game in which there is a combination of the elements of skill and chance in playing the game in that a missile follows an irregular path, and it is an object of a 5 player to catch such missile and thus release missiles for continued play.

My present invention may be considered as a further development of or improvement of my Patent No. 1,573,645, entitled Amusement device, 10 issued February 16, 1926.

In my present game, one of the objects and features thereof, is the use of a vertical game board on which there is a plurality of horizontal pins. At the upper end of the board a missile 15 may be inserted and dropped vertically of the board, preferably between the board and glass window. The pins cause the missile to follow a devious course. Associated with the game board and at the bottom I have a movable catching device which may be shifted transversely of the board below the pins with the object of catching the missile in its descent, and if the missile is so caught, a further feature of my invention is the releasing of a pocket or receptacle in which 25 missiles may accumulate.

A further object and feature of my invention is in connection with the game board providing a series of pockets or receptacles in which missiles may drop from the game board when they are 30 not caught, that is, until the missiles which are caught by the catching device are diverted from the pockets or receptacles.

A further object and feature of my invention is to release only the pocket or receptacle from 35 which the falling missile has been deflected by the catching device and therefore reward the player for successfully catching the missile.

A detailed feature of this portion of my invention relates to a trap-door or gate at the bottom 40 of each receptacle, and a releasing trigger which may be operated by a deflected missile, this missile being acted upon by a slideable plunger manipulated by the player as a further movement of a missile pocket device when inserting a missile.

A further feature of my invention relates to 45 adjustable partitions or deflecting arms which lead to the missile pockets whereby the missiles may operate the triggers. These deflectors may be adjusted in order to make it more difficult to 50 have missiles in certain missile pockets and corresponding to the releasable missile receptacles, than in other missile pockets, and these deflecting partitions are adjustable to vary the hazard. This feature can only be controlled by the person 55 installing the machine.

Another detailed feature of my invention is a device for closing the releasable pockets when they have been filled with missiles that have dropped in front of the game board and this comprises a closure gate actuated by the accumulated missiles to close this gate, and in so closing it, to divert the missile into the compartment having the missiles which have been used as a means to release missiles in the pockets.

My invention is illustrated in connection with 10 the accompanying drawings, in which:

Fig. 1 is a perspective exterior view of the game device as a whole.

Fig. 2 is a vertical section substantially on the line 2—2 of Figs. 1 and 4 in the direction of the 15 arrows.

Fig. 3 is a vertical section on the line 3—3 on Fig. 2 in the direction of the arrows.

Fig. 4 is an inclined transverse section on the line 4—4 of Fig. 2 in the direction of the arrows. 20

Fig. 5 is an enlarged detail of the tripping action for a missile receptacle trap-gate.

Fig. 6 is an enlarged vertical section on the line 2—2 showing the closure elements for the missile 25 pockets.

Referring first to the construction of Figs. 1 and 2, I employ a base 11 which is preferably rectangular and has a scooped out trough or pocket 12 on the upper side adjacent the front. A cabinet 13 is mounted on the base. This is illustrated 30 as having a back wall 14, a front wall 15, two end walls 16 and a top 17. The upper part of the front wall forms a game board 18 and this has a plurality of irregularly staggered pins 19, the pins 35 preferably being horizontal and the heads of the pins extending to a glass window 20 so that the missiles cannot position between the heads of the pins extending to the glass. A cross board 21 is located below the glass, there being a transverse slot 22 between the lower edge of the glass and the 40 upper edge of the board 21.

Forward of the front wall 15, that is, forward 45 of the lower portion thereof, there is a series of missile pockets or receptacles 23. The end pockets have end walls 24 formed preferably integral with the ends 16 of the cabinet and have intermediate partitions 25. They are all provided with glass windows 26. These pockets are closed at the bottom each by tilting trip or gate 27 which 50 is indicated as extending through an opening 28, there being one opening for each missile pocket in the front wall 15. The opening has an inclined surface 29 to allow the gates to tilt downwardly and each gate is secured to a hinge 30. Tension 55

I claim:

1. A game having an upright board, a transparent panel over the board, means providing an entrance for missiles at the top of the board, deflecting means between the board and panel for causing a descending missile to have an irregular and non-determinative path, means providing a plurality of pockets at the bottom of the board into any of which a descending missile may drop, 10 a catching means manually movable from the outside and adapted to be moved over the tops of the pockets in an attempt to catch missiles before entering the pockets, and means operable only upon a missile being caught by the catching 15 means for opening that pocket over which the missile is caught to release the missiles that have collected in such pocket.

2. A game having an upright board, a transparent panel over the board, means providing an entrance for missiles at the top of the board, 20 deflecting means between the board and panel for causing a descending missile to have an irregular and non-determinative path, means providing a plurality of pockets at the bottom of the board into any of which a descending missile may drop, a catching means manually movable from the outside and adapted to be moved over the tops of the pockets in an attempt to catch missiles before entering the pockets, pocket opening 25 means for each pocket, means for diverting the caught missile into the pocket opening means of the pocket over which the missile was caught, and means for causing the caught and diverted missile to open the pocket over which the missile 30 was caught to release the missiles collected 35 therein.

3. A game having an upright board, a transparent panel over the board, means providing an entrance for missiles at the top of the board, deflecting means between the board and panel for causing a descending missile to have an irregular and non-determinative path, means providing a plurality of pockets at the bottom of the board into any of which a descending missile may drop, a tubular catcher slidable over the tops of the pockets arranged to be used to attempt to catch 10 the descending missile, diverting means having a passage for each pocket into any of which a caught missile may be diverted by the catcher, and means operable through the medium of the caught and diverted missile for opening the pocket 15 over which the missile was caught to release missiles collected therein.

4. A game having an upright board, a transparent panel over the board, movable means for introducing a missile between the panel and the 20 board to enable it to descend therebetween, deflecting means between the board and panel for causing a descending missile to have an irregular and non-determinative path, means providing a plurality of pockets at the bottom of the board 25 into any of which a descending missile may drop, diverting means manually movable from the outside and arranged to be moved over the tops of the pockets in an attempt to divert the descending missile from dropping into a pocket, and means 30 operable by said movable means when a missile is diverted for opening the pocket over which the missile has been diverted to release the missiles that have collected in that pocket.

35
